UNITED STATES PATENT OFFICE.

EDWARDO GONZÁLEZ, OF SANTA BARBARA, CALIFORNIA.

COLLAR.

1,412,931.

Specification of Letters Patent. Patented Apr. 18, 1922.

Application filed April 18, 1921. Serial No. 462,240.

To all whom it may concern:

Be it known that I, EDWARDO GONZÁLEZ, a citizen of Mexico, residing at Santa Barbara, in the county of Santa Barbara and State of California, have invented a new and useful Collar, of which the following is a specification.

This invention relates to apparel, it being the primary object of the invention to 10 provide a novel means by which a cravat may be secured to a collar, to obviate the necessity of untying the cravat to remove the same.

A further object of the invention is to 15 provide means to permit the ready application of a made up cravat, in a manner to simulate a tied cravat.

A still further object of the invention is to provide means for applying a cravat to a 20 soft collar, eliminating the possibility of the wrinkling of the collar.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

Referring to the drawing:—

Figure 1 is a front elevational view of a 35 collar showing the neck tie as applied thereto, the collar being partly broken away to illustrate the connection between the collar folds.

Figure 2 is a modified form of securing 40 means; and

Figure 3 is a perspective view of a securing pin as employed with the structure as shown by Figure 1 of the drawing.

Referring to the drawing in detail, the 45 reference character 5 designates a collar which is of the usual construction, and as shown, the collar is provided with tabs 6 arranged in spaced relation with each other and secured to the collar adjacent to the ends 50 thereof.

Each of these tabs is formed of cloth material, having one end thereof formed into

a loop as indicated at 7, the loop of one tab being disposed in registry with the loop of the adjacent tab. 55

The cravat which is employed in connection with the collar, is of the made up type, and provided with extensions 8, each of which being provided with a loop 9 adapted to be positioned between the loops 7 of the 60 pairs of tabs 6, so that the loop 9 will register with the loops 7 of the tabs.

While the loops are in such registering positions, securing pins 10 are inserted in the loops, and as shown, these pins are provided with heads 11 to contact with the upper edge of the upper tab of each pair to restrict movement thereof. It might be further stated however that these pins 10 are formed preferably of rubber or other flexible material, which is capable of preventing displacement of the cravat with respect to the collar, but at the same time move with the movements of the collar incident to the user moving his body. 70 75

In the modified form of the invention as illustrated by Figure 2 of the drawing, the extensions 12 are provided with eyelets 13 to be positioned over the buttons 14 that are secured between the outer and inner folds 80 of the collar. From the foregoing it will be readily seen that a made up cravat may be secured to a collar, the same effect being presented as if the tie were placed around the collar and tied in position. 85

Having thus described the invention, what is claimed as new is:—

In a device of the character described, a collar having tabs arranged in spaced relation and disposed in pairs, a cravat having 90 extensions formed with loop portions, the loop portions adapted to be positioned between the tabs of the respective pairs, and means extending through the tabs and loop portions of the extensions for securing the 95 cravat to the collar.

In testimony that I claim the foregoing as my own, I have hereto affixed my signature in the presence of two witnesses..

EDWARDO GONZÁLEZ.

Witnesses:

F. N. GUTIERREZ,
MICHAEL BEATRICE.
